UNITED STATES PATENT OFFICE

110,914

DESIGN FOR A COMBINED WRITING TABLE AND CABINET OR SIMILAR ARTICLE

Charles E. Whitcomb, Bayside, Long Island, N. Y.

Application November 23, 1937, Serial No. 73,136

Term of patent 7 years

To all whom it may concern:

Be it known that I, Charles E. Whitcomb, a citizen of the United States, residing at Bayside, Long Island, in the county of Queens and State of New York, have invented a new, original, and ornamental Design for a Combined Writing Table and Cabinet or Similar Article, of which the following is a specification, reference being had to the accompanying drawings, forming part thereof.

In the drawings:

Fig. 1 is a perspective view of the combined writing table and cabinet or similar article, showing my new design in its closed position;

Fig. 2 and Fig. 3 are perspective views thereof, showing the design in opened position.

I claim:

The ornamental design for a combined writing table and cabinet or similar article, as shown.

CHARLES E. WHITCOMB.
